US0D1035566S

(12) **United States Design Patent** (10) Patent No.: **US D1,035,566 S**
(45) Date of Patent: ** Jul. 16, 2024

(54) **BATTERY PACK**(71) Applicant: **MILWAUKEE ELECTRIC TOOL CORPORATION**, Brookfield, WI (US)(72) Inventors: **David M. Schwalbach**, Milwaukee, WI (US); **Paul Rossetto**, Milwaukee, WI (US); **John G. Marx**, Hartford, WI (US); **Cameron R. Schulz**, Milwaukee, WI (US); **Joel D. Snyder**, Milwaukee, WI (US); **Wyatt R. Silha**, Milwaukee, WI (US); **Kyle C. Fassbender**, Brookfield, WI (US); **Mark E. Brouwer**, Hartford, WI (US)(73) Assignee: **MILWAUKEE ELECTRIC TOOL CORPORATION**, Brookfield, WI (US)(**) Term: **15 Years**(21) Appl. No.: **29/805,309**(22) Filed: **Aug. 26, 2021**
